(57) **CLAIM**

The ornamental design for a display screen or portion thereof with graphical user interface as shown and described.

DESCRIPTION

The file of this patent contains at least one drawing executed in color. Copies of this patent with color drawing(s) will be provided by the Office upon request and payment of the necessary fee.

FIG. 1 is a front view of a first embodiment of a display screen or portion thereof with graphical user interface showing the new design;

FIG. 2 is a front view of a second embodiment of a display screen or portion thereof with graphical user interface showing the new design;

FIG. 3 is a front view of a third embodiment of a display screen or portion thereof with graphical user interface showing the new design;

FIG. 4 is a front view of a fourth embodiment of a display screen or portion thereof with graphical user interface showing the new design; and,

FIG. 5 is a front view of a fifth embodiment of a display screen or portion thereof with graphical user interface showing the new design.

The outermost broken lines illustrate a display screen or portion thereof and form no part of the claimed design. The dash-dot-dash broken lines illustrate bounds of the claimed design. The ghosted regions illustrate features of a display
